LAMP MOUNTING FOR TOY VEHICLES

Herman L. Kraeft, Cleveland, Ohio, assignor to
The Murray-Ohio Manufacturing Company,
Cleveland, Ohio, a corporation of Ohio

Application July 10, 1933, Serial No. 679,685

1 Claim. (Cl. 240—7.1)

This invention pertains to vehicle toys provided with electric lighting systems, embodying miniature electric light or flash-light bulbs. The general object of the present invention is to provide a simple, efficient supporting means for head lights that is readily adaptable to toy vehicles, and which will permit the use of standard bulb constructions and sockets.

A more specific object of my invention is the provision of a novel bracket construction for supporting a miniature lamp socket and lamp, and which can be readily assembled in production regardless of slight variations in the dimensions of standard miniature bulbs and the sockets therefor.

Other objects of my invention will hereinafter become apparent from the following description, which refers to the accompanying drawing, illustrating a preferred embodiment thereof. The essential characteristics are summarized in the claim.

In the drawing, Fig. 1 is a side view of a miniature toy vehicle, equipped with my invention; Fig. 2 is a side view of my miniature bulb mounting, adaptable for attachment to the front fenders of the toy, as well as to the rear of the body thereof; Fig. 3 is a cross-section taken through the bracket and socket; Fig. 4 is a perspective view of the bracket per se; and Fig. 5 is a perspective view of a specially formed washer or disk which affords screw engagement with the body of the socket in a manner to be hereinafter described.

My invention contemplates the provision of a lamp mounting for miniature vehicle toys, comprising a one-piece stamped metal bracket formation, adaptable to support a miniature lamp socket, the body of which comprises the usual interiorly-exteriorly threaded sheet metal tube, one end of which is closed by an insulated means adapted to support a contact for a miniature bulb contact.

In the drawing, I show, in Figs. 2, 3 and 4, a pressed metal bracket, comprising an attachment base or lug 10, which may be rectangular, as shown, or be formed to any shape to be complementary to the shape of the particular part of the toy vehicle to which the bracket is to be attached. A perforation 11 is provided therein, whereby the bracket lug 10 may be securely clamped to the body member 12 of the vehicle by a rivet or bolt 14.

The bracket is provided with a lamp socket supporting branch 15, formed normal to the

base or lug 10, in a rounded manner to enhance the appearance thereof, and is provided with a central opening or aperture 16 of a diameter greater than the diameter of the body 17 of a lamp socket member 18. The portion 15 of the bracket is also provided with a flange 19, for the purpose of adding strength to the bracket, as well as to increase the attractiveness thereof. The socket 18 may be of the standard dimensions, but I provide a flange 20 at the bulb-receiving end thereof, the outer diameter of which is greater than the aperture 16 formed in the bracket portion 15, for a purpose to be described.

It will be noted, as shown in Fig. 3, that the socket 18 is provided with an insulating disk 21, formed of porcelain or other suitable insulating material, which supports the terminal end 22 of a battery wire 23, and the body 17 of the socket 18 is provided with a thread formation 24 for the reception of the threaded socket end of the miniature lamp 25. The threads 24 are usually formed by a rolling operation, and such rolling operation incidentally produces an external thread 26, which I utilize in the following manner.

To hold the socket member 18 in place, I provide a semi-flexible disk, Fig. 5, having a diameter substantially equal to the diameter of the bracket portion 15 of the bracket structure, and I perforate the disk in such a manner as to provide several tongues or prongs 31, which can be distorted, as shown in Fig. 3, to serve as an internal thread, adapted to engage the external thread 26 on the socket member 18. Thus, by screwing the washer 30 over the outside of the tubular body, the socket can be brought into a firmly mounted relation to the bracket, as shown in Fig. 3.

It will be apparent that this bracket construction, and the manner of attaching the socket to the bracket provides a conductive connection between the flange 20 of the socket and the bracket, which is firmly maintained by the disk 30. Also, if there is any variation in the length of the body of the socket, this variation can be corrected during the formation of the socket flange 20, so that positive connection between the lamp contact and socket contact is always assured when assembly is taking place in production quantities and the lamp 25 can always be screwed the full length of the socket to make contact with the terminal 22 of the socket.

I claim:

A lamp bracket for a toy vehicle, adapted to support a miniature lamp, comprising an ex-

teriorly threaded socket member having an annular flange adjacent one end thereof, an apertured metallic bracket member having an opening therein greater than the diameter of the threaded portion of said socket, but less than the diameter of the flange on said socket, a semi-flexible washer having an opening therein of greater diameter than the threaded portion of said socket and having a plurality of ears extending radially into said opening to engage the

threads of said socket and retain it in position projecting through the opening in said bracket, said bracket having an ear bent normal to the plane of the bracket and extending rearwardly therefrom for securing the bracket to the toy vehicle, and an annular flange formed on said bracket and extending forwardly therefrom to form a partial lamp housing for a lamp positioned in said socket.

HERMAN L. KRAEFT.
